[57] CLAIM

The ornamental design for a blood pressure testing kiosk, as shown and described.

DESCRIPTION

FIG. 1 is an isometric view of one embodiment of a blood

pressure testing kiosk showing our new design;

FIG. 2 is a front elevational view of the embodiment of FIG. 1;

FIG. 3 is a rear elevational view of the embodiment of FIG. 1;

FIG. 4 is a top plan view of the embodiment of FIG. 1;

FIG. 5 is a bottom plan view of the embodiment of FIG. 1;

FIG. 6 is a right side elevational view of the embodiment of FIG. 1;

FIG. 7 is a left side elevational view of the embodiment of FIG. 1;

FIG. 8 is an isometric view of another embodiment of a blood pressure testing kiosk showing our new design;

FIG. 9 is a front elevational view of the embodiment of FIG. 8;

FIG. 10 is a rear elevational view of the embodiment of FIG. 8;

FIG. 11 is a top plan view of the embodiment of FIG. 8;

FIG. 12 is a bottom plan view of the embodiment of FIG. 8;

FIG. 13 is a right side elevational view of the embodiment of FIG. 8; and,

FIG. 14 is a left side elevational view of the embodiment of FIG. 8.
